UNITED STATES PATENT OFFICE.

HARRY C. GAMMETER, OF BRATENAHL, OHIO, ASSIGNOR TO THE AMERICAN MULTIGRAPH COMPANY, OF CLEVELAND, OHIO, A CORPORATION OF OHIO.

TYPE-HOLDING DEVICE.

1,088,410.

Specification of Letters Patent.

Patented Feb. 24, 1914.

Application filed December 31, 1909. Serial No. 535,747.

To all whom it may concern:

Be it known that I, HARRY C. GAMMETER, a citizen of the United States, residing at Bratenahl, in the county of Cuyahoga and 5 State of Ohio, have invented a certain new and useful Improvement in Type-Holding Devices, of which the following is a full, clear, and exact description, reference being had to the accompanying drawings.

10 The object of this invention is to provide a very simple and efficient holder for a line of individual type made up into an address. My invention provides an address plate adapted to receive and hold a plurality of 15 parallel lines of individual type, there being means for quickly securing said plate in place or releasing it, as desired. My plate when loaded and in place may form a portion of a printing couple or a type assem- 20 bling or distributing machine, or a combined machine which has assemblage, distribution and printing features after the manner of the multigraph.

The particular characteristics of the present invention are hereinafter more fully described and are summarized in the claims.

In the drawing—Figure 1 is a perspective view of my address plate unloaded; Fig. 2 is a plan of such plate loaded and in place, 30 together with the holding mechanism therefor; Fig. 3 is a cross section of the structure shown in Fig. 2; Fig. 4 is a perspective of type which may be employed with my address plate; and Fig. 5 is an enlarged cross 35 section showing the stop for the type.

Referring to the parts by reference numerals, 10 indicates the address plate itself. This is a thin plate, preferably of metal, which may be flat or curved, according to 40 whether it is designed to be used on a flat bed machine or one where the form turns about a concentric axis. In the illustration it is curved for the latter use. The plate has a plurality of slots 11 extending from one 45 end well toward the other end. In the drawing there are three of these slots. Near their open ends the slots flare, as shown at 12. On the edges of the plate are suitable notches, as, for example, the notch 13 on one 50 side and the notches 14 and 15 on the opposite side.

The type which co-operates with the address plate has grooves on its opposite sides, as shown in the case of the type 20 in Fig. 54. The type there shown has also a beveled

foot 21 which is of use in assembling and distributing, but is not employed unless desired. Such type with the grooved sides and beveled feet are claimed in my Patent #836,026, issued November 13, 1906. 60

When the type are inserted in the slots 11 they are shoved up against the ends of the slots, as shown in Fig. 2. In this position they are held by suitable elastic plugs 30 which are preferably of rubber and are of 65 the form shown in Fig. 5; that is, these plugs are approximately cylindrical in shape, with grooves on their opposite sides, and the shank of the plug between the grooves is of less width than the distance across the slots 70 11, while the up and down dimension of the groove shown in Fig. 5, when the plug is removed, is less than the thickness of the plate. The result is that when the plug has been put in place it holds itself there by 75 clamping the top and bottom surfaces of the plate and has no tendency to spread or spring the tines of the plate between the slots.

Fig. 2 shows my plate loaded and in place 80 on a member 40 provided with rails 41 having overhanging edges and formed to carry between them rows of individual type of the same character as is carried by the plate itself. The member 40 shown is curved and 85 indicates a cylindrical segment or a complete rotatable drum. Such drum or segment may co-operate with a suitable platen (not shown) making a printing couple. A certain portion of the printing member 40 has the upper 90 portions or treads of the rails omitted, as shown at 42. The address plate is substantially of the thickness of the heads of these rails, so that the plate may be seated on the webs 43, remaining in the cut-out portion, 95 and stand with its outer surface alined with the outer surface of the remaining rails, the webs 43 supporting the plate between the type rows. In other words, the tines of the plate take the place of the heads of corresponding rails. When in place in the recess which is provided in the printing member, the plate may be held in place by suitable 100 clips 50 and 60. The clip 50 is a sheet metal member riveted to a rib 52 on its underside, which is formed to slide between adjacent rails and stand beneath their heads. This structure engages the rails preferably with sufficient friction, so that it holds itself in place. This clip 50 has a down-turned lip 53 105 110

which extends into the recess 42 occupied by the address plate. When the address plate is in place it stands beneath the clip 50 and its notch 13 embraces the tongue 53.

5 The clip 60 referred to is movably mounted on the printing member on the other side of the address plate from the clip 50. This movable mounting is provided by a suitable rib 62 on the underside of the plate riveted 10 to it, but sliding freely enough between the rails so that the plate may be easily shifted. This plate 60 is preferably roughened or corrugated on its upper side, as shown at 61, whereby it may be easily shifted by the operator's finger. The plate 60 has a pair of tongues 63 and 64 adapted to overhang the openings 14 and 15 of the address plate, or spaces between these openings and between the opening 15 and the adjacent end of the 20 plate, respectively, according to the position of the clip 60. When the tongues 63 and 64 aline with the openings 14 and 15 the address plate may be easily removed by being tipped up at that side and drawn out 25 diagonally over the clip 60. When the tongues do not so aline the plate is held in place. To enable the easy removal of the plate, I provide a spring 70 lying in the groove between two rail webs and beneath 30 the free edge of the plate. This spring need not be anything more than a spring wire. It operates to elevate the edge of the plate when the clip 60 allows it, thereby increasing the ease of removal. A suitable plug, as 80, 35 inserted between two of the adjacent rails may form a stop for the movement of the clip 60.

Such an address plate as described may be very conveniently loaded either by hand 40 or by a suitable assembling machine. In either case the type are shoved in from the open end of the plate and plugs 80 are installed, being shoved in from the open end. The machine assemblage may be of the 45 character set out in my Patent #722,404, in which case the plate may simply occupy a recess in the periphery of the printing drum, the slots of the plate alining with the journals between adjacent rails. As shown 50 herein, in Fig. 2, the position of the plate on the printing member may be adjusted lengthwise of the rails to give the address the desired position with reference to the body of the letter, it being understood that 55 the body of the letter is composed of individual type carried by rails parallel with the address plate. As shown in Fig. 2, 90 is a suitable marginal stop for limiting the edge of the page form. The edge of the address 60 may aline therewith, as shown, or it may be shifted either way in the recess 42. When the plate is brought to the extreme left-hand end of the recess in Fig. 2, the tines of the plate abut with the ends of rail heads, and 65 type comprising addresses set up on the

printing member may be shoved into the address plate.

When once loaded, my plate will hold its type securely in place against accidental removal. The simple removal of the plugs, however, enables the type to be removed as desired. When loaded, my plates may be installed and removed with great rapidity, by the operator using one hand. He may hold the plate with his thumb and first finger adjacent to the edge having the two notches 14 and 15 and tuck it under the clip 50 and then depress it by the thumb into the recess against the light spring 70, and then with one of his fingers shove the clip 60 to 70 override the plate. The plate may be removed with equal ease by shoving the clip by the operator's finger and grasping the free edge of the plate which is then lifted 75 by the spring 70. 80

Having thus described my invention, what I claim is:

1. The combination, with a plate having a plurality of slots extending from its extreme end, type grooved on its opposite sides and adapted to occupy the slots, and a printing member having means for holding said plate and rails alining with the tines of the plate between the slots. 90

2. An address plate having a curved thin body with a plurality of parallel slots extending from one end of the plate toward the other end and being open at one end, combined with a rotatable member having a recess for said plate and having longitudinal rails adapted to aline with the tines of the plate between the slots. 100

3. A fastening device for type comprising a slotted plate, grooved type adapted to occupy the same and be held thereby, a printing member having an exterior recess for said plate and having type channels alining with the slots of the plate when it is in the recess, and a slideable clip adapted to override the plate to hold it in place in 110 the recess. 105

4. In a fastening device for type, the combination of a slotted plate having a notched edge, a slideable clip having a tongue which may pass through such notch and override 115 the plate adjacent thereto, and a clip for holding the other edge of the plate.

5. The combination, with a curved member having parallel overhanging longitudinal rails, of a typeholding plate adapted to occupy a recessed portion in such railed member and having separated type lines alining with spaces between the rails, and a clip for holding the plate in place. 120

6. In a type-holding device, the combination of a member having parallel rails with overhanging edges, a portion of said member having the heads of the rails absent but the webs present, and a type-holding plate adapted to occupy such portion and having 130

a thickness substantially equal to the omitted portions of the rails.

7. In a type-holding device, the combination of a curved member having a plurality of parallel rails with overhanging heads, the heads of the rails being cut away at a certain place; a plate adapted to occupy such cut-away portion and have its inner surface rest on the webs of the cut rails and its outer surface flush with the outer surface of the uncut rails, said plate having slots adapted to aline with the slots between adjacent rails, and type grooved on its opposite sides and occupying the slots of the plate.

8. The combination of a member having headed parallel rails, a portion of which are recessed, an address plate adapted to occupy such recess, a pair of clips for holding said plate, each clip resting on such rails and being provided with members extending beneath the rail heads.

9. The combination of a member having parallel rails with overhanging heads, an address plate adapted to occupy a recess in such rails, a pair of clips for holding said plate, each clip resting on such rails and being provided with members extending beneath the rail heads, one of said clips being slidable and being provided with a tongue adapted to register with a notch in the edge of the plate or overhang the plate adjacent to the notch.

10. The combination with an address plate slotted from one end and having a notch in one edge, of a clip formed to overhang the plate at that edge and having a tongue which may occupy the notch, said plate having a notch on its opposite edge, and a slidable clip having a tongue adapted to be passed through the notch and override the plate adjacent thereto.

11. In a typeholding device, the combination of a recessed member, a plate adapted to seat therein, means for holding one edge of the plate, a spring tending to swing the plate about its held edge as a center to move the other edge of the plate out of the recess, and means adapted to overhang the last-mentioned edge of the plate and hold the same in place.

12. The combination, with a curved railed member adapted to carry a page form, of a plate shorter than the member and adapted to carry an address and removably mounted on the exterior of such member with the space between the address lines alining with certain rails beyond the end of the plate.

13. The combination, with a curved railed member adapted to carry a page form, of a slotted plate adapted to carry an address composed of type projecting above and below the plate and removably mounted on such member, said plate occupying a re-

cess in the exterior surface of the railed member with the outer surface of the plate peripherally alining with the member carrying the page form and the plate intermediately supported between type lines.

70

14. The combination with a railed member for carrying type, said member having a recessed portion, an address plate adapted to occupy such recessed portion and having type extending above and below the plate, said member having ribs extending between adjacent rows of such type and supporting the plate.

75

15. The combination of a plate formed with slots extending to its extreme end, type grooved on its opposite sides occupying the slots so formed, and a suitable support for the plate having a recess which the plate may occupy and ribs extending between adjacent slots.

80

16. The combination of a plate formed with slots extending to its extreme end, type grooved on its opposite sides occupying the slots so formed, a suitable support for the plate having ribs extending between adjacent slots, and a slidable clip for locking and releasing the plate.

90

17. The combination with an address plate slotted from its extreme end, of type grooved on its opposite sides and occupying such slots, and plugs for holding the type in place, said plugs being elastic and occupying the slots and engaging the top and bottom of the plate without engaging the edges thereof at the slots.

95

18. The combination with a slotted plate adapted to carry grooved type, of an elastic stop plug occupying such slot and overhanging both surfaces of the plate while free from the walls in the slot of the plate.

100

19. The combination of a curved member having parallel ribs and a curved removable address plate having type with projecting feet, and means engaging the plate above and below the address for holding the plate on said member with rows of type feet on opposite sides of a rib.

110

20. The combination with a rotatable member having parallel overhanging rails arranged longitudinally to make an arcual surface, of a curved type-holding plate adapted to occupy a recessed portion in such railed member, and means for holding the plate in place with its type line alining with the channels between the rails.

115

21. The combination of a plate formed with slots extending to its extreme end, type grooved on its opposite sides occupying the slots so formed, and a rotatable drum adapted to carry the plate and having ribs extending between adjacent slots and overhanging rails adapted to aline with the tines of the plate.

120

22. The combination of a rotary member, a curved address plate adapted to seat there-

130

- on, said plate having parallel slots occupied by grooved individual type, and the rotary member having means for supporting the plate between the type lines.
- 5 23. The combination of a rotary member having a recess, an address plate adapted to seat therein, said plate having parallel slots occupied by lines of grooved individual type, and the rotary member having ribs in the 10 recess for supporting the plate between the type lines.
- 15 24. The combination of a slotted plate adapted to carry a line of grooved type, and a stop for such line, said stop occupying such slot and overhanging both surfaces of the plate while free from the walls of the slot of the plate.
- 20 25. The combination, with a curved railed member adapted to carry a page form, of a slotted plate adapted to carry an address of grooved type extending above and below the plate, said plate being removably mounted on the exterior of such member with the space between the address lines alining with 25 certain rails, and means for supporting the plate between its type lines.
- 30 26. The combination, with a grooved railed member adapted to carry a page form of lines of type, of a plate shorter than the railed member and adapted to carry a plurality of lines of type, and means for removably holding the plate on the member with its type lines longitudinally alining with channels provided by the rails.
- 35 27. The combination, with a rotatable member having parallel overhanging rails arranged longitudinally to make an arcual surface, of a curved slotted typeholding plate adapted to occupy a recessed portion in such 40 railed member with the type held between the slots alining with the type held between the rails, and means for holding the plate in place and supporting it between its type lines.
28. A printing member having parallel typeholding rails, and an address plate removably carried by said member and consisting of a furcated plate and individual type mounted between tines corresponding to the rail heads. 45
- 50 29. The combination of a railed member having a recess, a removable address plate having parallel typeholding edges, and means for holding the plate in the recess with the typeholding edges thereof alining with rails of the railed member. 55
30. The combination of a member having parallel rails with overhanging edges adapted to hold between them lines of type grooved on their opposite sides, a removable typeholder having means for holding parallel lines of type, and means for holding said typeholder on the member with the type lines thereof alining with spaces between rails on said member. 60
- 65 31. The combination of a member having parallel rails with overhanging edges adapted to hold between them lines of type grooved on their opposite sides, a removable typeholder having means for holding parallel lines of type, means for holding said typeholder on the member with the type lines thereof alining with spaces between rails on said member, and ribs carried by the member and adapted to support the typeholder between the type lines. 70
- 75 In testimony whereof, I hereunto affix my signature in the presence of two witnesses.
